RHEOSTAT

Samuel L. Richman, White Plains, and Arthur Fitchman, Yonkers, N. Y., assignors to Sono-tone Corporation, Elmsford, N. Y., a corporation of New York

Application March 2, 1949, Serial No. 79,194

3 Claims. (Cl. 201—55)

1

This invention relates to rheostat devices, and more particularly to rotary rheostat or potentiometer devices of the general type used in hearing aids, radio receivers, and other devices requiring small compact rheostats.

Among the objects of the invention is a novel rheostat device of the foregoing type which is extremely small and compact and assures that the frictional forces resisting rotary motion or displacement of the rotary rheostat member from the desired setting are controlled independently of any forces determining the pressure with which the slider contact is resiliently biased into contact engagement with different peripheral portions of the resistance element of the device.

The foregoing and other objects of the invention will be best understood from the following description of exemplifications thereof, reference being had to the accompanying drawings, wherein:

Fig. 1 is a plan view of the inner side of the rheostat shown in Fig. 2, with the bottom wall removed;

Fig. 2 is a cross-sectional view of the rheostat device, along the lines 2—2 of Fig. 1;

Fig. 3 is a plan view of the inner side of the bottom wall member of the rheostat of Figs. 1 and 2;

Fig. 4 is a cross-sectional view along the lines 4—4 of Fig. 1;

Fig. 5 is a view similar to Fig. 1 of another form of rheostat device of the invention, as shown in Fig. 6; and

Figs. 6 and 7 are cross-sectional views along lines 6—6 and 7—7 of Figs. 5 and 6, respectively.

The rheostat devices shown were invented for use as a part of a wearable amplified hearing aid having extremely small overall dimensions, small enough to fit into a vest pocket of a person.

Referring to Figs. 1 to 4, the rheostat exemplifying one form of the invention is made in the shape of a tiny flat casing structure comprising a rotary wall member 11 and a supporting wall member 12, which are rotatably joined to each other along a central axis. In the form shown, the casing structure in which all the operating parts are housed has an outer diameter of only .750 inch and its overall height is only .250 inch. The cooperating casing wall members 11 and 12 are made of plastic or moldable insulating material and are designed to interfit and to prevent dust, dirt or other foreign matter from entering the interior space 13 of the casing, while permitting revolvable motion between the rotary

2

wall member 11 and the supporting wall member 12. In the form shown, this is accomplished by providing the rotary wall member 11 with a circular border wall 14 overlapping a flanged circular rim portion 15 of the supporting wall member 12.

The two casing wall members 11 and 12 are shown provided with a revolvable junction structure comprising two interfitting cooperating junction members 17 and 18 of metal, extending from the central portions of the two casing wall members 11 and 12, respectively. The junction member 17 is shown in the form of a pin or shaft having an enlarged flanged head with a hollow rivet extension 21 seated and affixed in the obvious way shown to the rotary wall member 11, within its central opening portion, so that it forms a fixed part thereof. The cooperating junction member 18 is shown formed of a hollow cylindrical bushing provided along an intermediate portion thereof with an enlarged flange portion 23 seated and affixed to the central portion of the supporting wall member 12 within its central opening. The flanged portion 23 of the bushing 18 has a hollow rivet extension serving to affix and secure the hollow bushing member 18 to an interfitting shoulder portion of the wall member 12, so that the junction member bushing 18 forms a fixed part of the supporting wall member 12.

As seen in Figs. 1 and 2, the wider flanged portions 19 and 23 of the junction shaft 17 and junction bushing 18 are of hexagonal shape, so that by their engagement with correspondingly shaped portions of their seating openings of the two casing wall members 11 and 12 they are affixed against rotation relative to the wall members to which they are secured. The two wall members are readily assembled by simply slipping the shaft member 17 of the wall member 11 into the axial journaling opening of the bushing sleeve 18, the shaft 17 being retained in its position by a split spring ring 26 sprung into the locking groove formed in the end of the pivot shaft 17. The exposed outer end portion of the bushing 18 is provided with a thread making it possible to secure it, as by a nut, in its position on a chassis or frame of a device in which it is to be used.

Within the interior of the rheostat casing is mounted an arcuate or ring-shaped resistance element 31 carried by one wall member and arranged for cooperation with a contact element 32 of a contact arm structure 33 carried by the other wall member, so that by rotating one of

the wall members relative to the other, the contact element 32 will slide and maintain good electrical contact engagement with the different peripheral portions of the ring-shaped resistance element 31. The arcuate resistance element 31 is of the conventional type and may consist of a circular strip of electrically insulating material coated with a film of resistance material. Alternatively, the entire body of the ring-shaped resistance element 31 may be made of a resistance material. As a further alternative, an arcuate surface portion of the inner surface of the support wall member 12 may be coated with a film of resistance material to provide the resistance element. In the form shown, the resistance element 31 is arranged to form a fixed inwardly exposed arcuate resistance element of the support wall member 12, arranged to be engaged by the contact element 32 in each of its different angular portions thereof.

The contact arm structure 33 is made of a suitable electrically conducting spring metal, such as beryllium or copper, provided with a central seating collar 34 having a flange 36 with a circular opening by means of which it is seated on the inwardly projecting bushing portion 25 of the supporting wall member 12 for rotation around it. In the particular device shown in Fig. 1, the contact arm structure 33 extending from its seating collar 34 is made in the form of an arcuate loop provided at its outer end with a socket portion 35 holding therein the contact element 32 which is pressed against the resistance element 31. The elastic body of the contact structure 33, 34 is deformed so that when its collar 34 is retained in the central position shown, resting with its central portion against the flange 23 of the bushing member 18, the contact arm structure 33 will be elastically deformed and exert on its contact element 32 elastic restoring forces which subject the contact element to contact forces of a desired magnitude for maintaining proper electrical sliding contact connection with different peripheral elements of the ring-shaped resistance element 31, depending on the angular position of the arm structure 33.

In the particular rheostat structure shown in Figs. 1 to 4, the contact arm structure 33 is held affixed for rotation with the rotary wall member 11 by the engagement of a rearwardly extending retainer arm 37 within a locking recess 38 provided on the inwardly facing surface of the rotary wall member 11.

The rotary wall member 11 is shown provided with small inward projections or bosses 41 shaped to deflect facing arm portions of the arm structure 33 in the direction toward the cooperating wall member 12 carrying the resistance element, thereby elastically deforming the arms of the resilient contact arm structure 33 to provide the required elastic forces for pressing the contact element 32.

In order to limit the range of the arcuate motion of the two casing wall members 11, 12, they are shown provided with inwardly extending stop projections 42, 43 which limit the movement of the rotary wall member 11 to an angle corresponding to the arcuate length of the resistance element 31.

A connector pin 48 of metal, molded in the support wall member 11, provides a terminal connection to one end of the resistance element 31.

In a rheostat of the type described, it is desired that the rotary wall members should be retained in any one of the different peripheral set-

tings of its contact element 32. Heretofore, such rheostat devices depended on the elastic forces exerted by the contact arm and its contact element on the resistance element for retaining the contact element in its different peripheral setting and for resisting displacement of the two rotatably joined rheostat members. However, such prior art rheostat devices have always been a source of trouble because, when designed to retain the contact arm in the different selected settings, the pressure exerted by the contact element on the resistance element had to be made relatively large, with the result that the resistance element and the contact element had to be subjected to excessive wear.

According to the invention, the difficulties connected with such prior art rheostats are eliminated by providing an independent resilient biasing means to control the magnitude of the frictional forces resisting rotation of the two revolvably joined rheostat members of such rheostat devices, making it possible to provide for independent control of the resilient forces exerted by the contact element on the resistance element.

The additional independent rotary motion control means of the invention is so combined with the other elements of such rheostat device as to make it unnecessary to increase its overall dimensions and without materially adding to its manufacturing costs.

In the form of the device shown in Figs. 1 to 4, the additional motion controlling spring means is supplied by a conventional elastically-compressed helical coil spring 45 placed surrounding bushing portion 25 of member 12 and held compressed between the inner surface portion of the rotary wall member 11 and the circular central collar flange 36 of the contact arm 33, for pressing the rotating collar flange 36 against the central portion of the fixed wall member 12 and providing the desired independent rotation-resisting forces. With such an arrangement, the helical contact spring 45 may be readily given the desired spring action by elongating it or shortening it in production, so that when it is placed in position around the junction structure, it will press the collar flange 37 carried by the rotary wall member 11 with a definite force against the facing central metal flange 23 of the fixed wall member 12 to provide therebetween a controlled frictional engagement resisting arcuate displacement of the rotary wall member 11 from one rheostat contact position to another—without in any way modifying the forces with which the elastically deformed arm elements of the contact arm structure 33 hold the contact element 31 in sliding contact engagement with an arcuate portion of the rheostat element 31.

Figs. 5, 6 and 7 show a rheostat device of the invention generally similar to that of Figs. 1 to 4, but provided with another form of spring means supplying independent motion-resisting forces restraining the two rheostat wall members against displacement from an adjusted rheostat position without modifying the spring forces which maintain the desired contact pressure between the contact arm and the arcuate resistance element. The various elements of the rheostat device of Figs. 5, 6 and 7 are designated by a prefix "2—", followed by the same reference numeral as the corresponding element of Figs. 1 to 4.

In the rheostat device of Figs. 5, 6 and 7, two deflector projections 2-41 extending from the inner surface of the rotary wall member 2-11

serve to elastically deflect the two arcuate arm portions of the contact arm structure 2-33 for providing the desired elastic biasing force of the spring contact arm structure 33, maintaining the desired sliding contact pressure between its contact element 2-32 and the facing portion of the arcuate resistance element 2-31.

The spring arm structure 2-33 has a collar portion 2-34 seated around the inner bushing portion 2-25 of the fixed wall member 2-12 and resting against its underlying metallic bushing flange 2-25. The independent rotary motion-resisting action is provided by a spring member of sheet metal generally designated 61. The spring member 61 has a plurality of spring arms 62 engaging with their ends inward seating recesses 63 of the rotary wall member 2-11 for pressing a central collar portion 64 of the spring member 61 against the underlying circular collar 2-34 of the contact arm structure 2-33 with a desired independent control force fixing the frictional forces which resist arcuate deflection of the contact arm wall member 2-11 with its contact arm structure 2-33 from a desired adjusted position.

The principles of the invention explained in connection with specific exemplifications thereof will suggest to those skilled in the art many other applications and modifications of the same. It is accordingly desired that, in construing the breadth of the appended claims, they shall not be limited to the specific details shown and described in connection with exemplifications thereof.

What is claimed is:

1. In a rheostat device: a contact actuating wall structure having an integral central metallic junction member and a rheostat wall structure having an integral central metallic junction member; said two wall structures having inwardly facing surfaces and interfitting circular border portions surrounding said inwardly facing surfaces and confining between them a shallow generally circular interior space; one of said junction members being rotatably seated in a coaxial seating opening of the other of said two junction members and extending beyond the opposite ends of said other of said junction members and forming therewith a metallic junction structure rotatably joining said two wall structures; the junction member of said rheostat wall structure having a central inwardly facing circular guide surface and said rheostat wall structure having a relatively fixed inwardly facing resistance element generally concentric with said

junction structure; a rotatable electrically-conducting contactor structure having a central flat circular collar element surrounding said junction structure and engaging said circular guide surface and a resilient contact arm structure extending from said collar and including a contact element resiliently urged by said arm structure into sliding contact engagement with different peripheral portions of said resistance element; said contact structure having a retainer arm extending from said collar diametrically opposite from said contact arm element into interlocking engagement with a recessed portion of said actuating wall for rotation therewith; and an independent spring structure encircling said junction member and held compressed between an inwardly facing surface of the junction member of said actuating wall structure and the facing circular surface of said collar compressing said collar into frictional contact engagement with said circular guide surface of the junction member of said rheostat wall structure for controlling the frictional forces resisting rotary motion of one wall structure relative to the other wall structure without substantially modifying the resilient forces exerted by said contact arm structure on said resistance element.

2. In a rheostat device as claimed in claim 1, said spring structure being formed of a coil spring having an end coil turn engaging the facing surface of said collar, the opposite coil end turn of said spring engaging a facing circular surface portion of said actuating wall structure.

3. In a rheostat device as claimed in claim 1, said spring structure formed of a resilient spring sheet member having a central collar portion overlying the central collar element of said contact structure and a plurality of spring arms extending toward interengagement with inwardly facing surface portions of said actuating wall structure.
